ATTORNEY

UNITED STATES PATENT OFFICE.

OTTO T. PAPKE, OF JOLIET, ILLINOIS.

DEVICE FOR INDICATING THE FAULTY OPERATION OF IGNITION-VALVES AND CARBURETERS OF INTERNAL-COMBUSTION ENGINES.

1,286,751.

Specification of Letters Patent. Patented Dec. 3, 1918.

Application filed March 26, 1918. Serial No. 224,794.

To all whom it may concern:

Be it known that I, Otto T. PAPKE, a German subject, residing at Joliet, in the county of Will and State of Illinois, have invented 5 certain new and useful Improvements in Devices for Indicating the Faulty Operation of Ignition-Valves and Carbureters of Internal-Combustion Engines, of which the following is a specification.

10 This invention is a device for indicating the faulty operation of ignition-valves, and carbureters of internal combustion engines, and is more particularly adapted for use by owners, operators, and repair men, wherein 15 the device may be employed either permanently or temporarily as is desired, and when used temporarily, loose parts, such as chains, screw drivers, hammers, and unnecessary wires, are avoided.

20 One object of the invention is to provide a device for testing wherein each and all of the circuits leading to the spark plugs may be opened or short circuited by grounding.

25 Another object of the invention is to provide a supplementary spark gap to visually denote the sparking condition of the ignition system.

The shop method of testing ignition is by 30 short circuiting the spark plugs by means of a screw driver, hammer, or other metallic object. This does not always produce a good contact for grounding. Again when it is desired to test the spark plug to see 35 whether current is passing to the sparking points, the lead wire is detached and held a short distance away from the terminal. Both of these methods are make shifts but are commonly employed.

40 To avoid such methods this instrument is devised and its construction and assembly are such that it may be as readily used as the old method. At the same time it will be more accurate with less trouble in attaching 45 and connecting.

The invention broadly stated comprises a base formed of insulating material and having a groove extending longitudinally, a 50 spaced V-shaped recesses in the base, a switch blade pivotally mounted in each of the recesses, a pair of spaced terminals in each of the recesses and adapted to coöperate with the switch blade, a plurality of 55 sages for receiving conductors, one of said

conductors having a spark gap therein, the terminals of which are disposed in the groove and beneath the cover, the other terminals of the conductors being connected, respectively, to a switch terminal and a 60 spark plug, another conductor for connecting the switch blade to a coil terminal, and another conductor connecting the other switch terminal to a ground connection, said switch blade being adapted to open the circuit leading to a spark plug or to cut out the spark plug by grounding the coil connection. 65

One practical form of construction and assembly will be described and illustrated in 70 the accompanying drawings, in which:—

Figure 1 is a diagrammatic view with the engine and coil shown in dotted lines and the device in perspective,

Fig. 2 is a top plan view of the assembled 75 device, and

Fig. 3 is a sectional view on the line 3—3 of Fig. 2.

In the preferred embodiment about to be described there is provided a base 5 preferably formed of some suitable insulating material such as hard rubber or fiber. The upper side 6 of the base 5 is provided with a groove 7 that extends longitudinally thereof. As shown this groove 7 is approximately 80 rectangular. The groove has its side walls provided with other grooves indicated at 8 and 9 which latter grooves are preferably in alinement and are adapted to receive a cover 10 that may be formed of glass. 85

The base 5 is provided with a series of transversely arranged approximately V-shaped recesses 11, 12, 13, 14, 15, and 16. Each one of the recesses 11 to 16 inclusive is provided with the shouldered portions indicated at 17 and 18. These shouldered portions 17 are adapted to receive and form seats for the terminals 19, 20, 21, 22, 23, and 24. These terminals are preferably of the same width as the width of the recesses and are provided with suitable holes so that the screws 25 may pass therethrough and be engaged with the base 5. 95

The terminals 19 to 24 inclusive are provided with a slanting or sloping side 24 100 which slope or slant is approximately the same as the slope or slant of the V-shaped recesses in which it is seated. The shoulders 18 are adapted to receive similar terminals indicated at 27, 28, 29, 30, 31, and 32. These 110

terminals are also held in position by means of the screws 33.

The terminals 27 to 32 inclusive are each connected to a ground wire or common conductor 34 that is placed in a suitable passage extending longitudinally of the base 5. In each of the recesses 11 to 16 there is pivotally mounted a switch blade 35. Each of the switch blades is provided with a handle 10 as indicated at 36, 37, 38, 39, 40, and 41. The pivotal connection for the blade being indicated at 42 in Fig. 3.

Each one of the switch blades has connected to it a conductor 43, one of which is 15 illustrated in Fig. 3. These conductors 43 pass through the passages 44 that are formed transversely of the base 5. The passages 44 may be provided with a counter bored portion 45 so that the end of the insulated 20 cable 46 may be provided with a terminal.

The terminals for each one of the cables 46 are indicated at 47, 48, 49, 50, 51, and 52. The terminals 47 to 52 inclusive connect with the leads 53, 54, 55, 56, 57, and 58 that come 25 from the terminals of the coil box A. As shown the conductors 43 pass through the base 5 substantially parallel to its underside so as to directly connect with the switch blades 35.

30 Each one of the terminals 19 to 24 inclusive has connected to it a short rod, the rods being indicated at 59, 60, 61, 62, 63, and 64. These rods 59 to 64 inclusive extend through suitable passages that are so arranged that 35 the terminals of these rods are in the groove 7 and below the cover 10. A passage 65 is formed in alignment with the passage that receives the short rods and this passage is also adapted to receive rods 66, 67, 68, 69, 70 40 and 71.

The ends of the rods 66 to 71 inclusive are spaced from the ends of the rods 59 to 64 inclusive. The spacing providing a gap space has a supplementary spark gap. Each 45 one of the passages 65 may be provided concentric thereto with counter bored portions 72, one of which is indicated in Fig. 3. These counter bored portions are adapted to receive the ends of the cables 73, 74, 75, 76, 50 77, and 78. The cables 73 to 78 inclusive are provided with terminals for connecting with the spark plugs indicated at 79, 80, 81, 82, 83, and 84. One of the terminals being indicated at 85 in Fig. 3.

55 The spark plugs 79 to 84 are mounted in the usual place in the engine B shown in dotted lines in Fig. 1. As shown in Fig. 1 the conductor 34 connects with the cable 85 having the terminal 86. This terminal 86 is 60 preferably connected to the engine at 87 so as to form a grounding point.

In connecting up the device as shown in Fig. 1 the ground terminal is connected at some suitable point upon the engine as indicated at 87. The switch handles 36 to 41

are moved over so that the switch blades 35 contact with the switch terminals 19 to 24 inclusive. If the system is in good condition the sparks passing between the supplementary gaps carried in the grooves 7 will show 70 by the regularity of the sparks passing between the sparking terminals 59 to 64 inclusive and 66 to 71 inclusive.

If the spark passing through the supplementary gap is thin and stringy or is very 75 fat the spark plug points should be adjusted. If the spark plugs are in good condition and the gaps thereof are the correct size and then there is irregular sparking at the supplementary gaps it would indicate that there is 80 trouble in the ignition system.

If the battery and generator connections are good and there is sufficient current passing and the sparking is still poor the trouble will then be found in the wires, switch, distributor, contact breaker, coil or contact maker. In order to test each one of the 85 spark plugs separately the switch handles may be moved over so that they will contact with the switch blade terminals 27 to 32 in- 90 clusive.

As each switch blade 35 comes in contact with one of these last named terminals the circuit leading and its respective spark plug will be grounded through the conductor 34 95 and therefore no action will take place in the cylinder. In order to test for valve grinding all of the cylinders except one should be grounded so that no explosions 100 will take place therein.

Misfiring may then be indicated by faulty ignition, too lean or too rich a mixture from the carburetor, faulty spark plug, faulty valves or poor compression. By this means each one of the cylinders may be tested separately and independently merely by moving the switch handles 36 to 41 that control the movement of the switch blades 35.

By confining the operation of the engine to a single cylinder delivering power, the several defects of the engine may be more easily found. Thus connecting rod bearing knocks, piston slaps, loose or worn piston pins and their bushing may readily be found as the engine cylinder is delivering power and approximates a load condition.

What is claimed is:

1. A testing device, which comprises a base formed of insulating material, said base having a longitudinally extending groove near one side, a cover for the groove, terminals for connecting with the spark plugs, coils, and a ground, and switching means for connecting the coil terminals to the ground.

2. A testing device, which comprises a base formed of insulating material and having a groove extending longitudinally thereof, said base being provided with spaced approximately V-shaped recesses, terminals in 130

the recesses, a switch blade pivotally mounted in each recess and adapted to engage with the terminals, a conductor connected to each switch blade and adapted to be connected to 5 a coil terminal, a conductor adapted to be connected with a spark plug and having a spark gap therein, said spark gap being disposed in the groove and having one of its points connected to a recess terminal, the 10 other and opposite recess terminals being connected to a common conductor adapted to form a ground connection.

3. A testing device, which comprises a base, a plurality of approximately V-shaped 15 recesses having shouldered portions at their upper ends, a slanting face switch terminal mounted and secured in each shouldered portion, a switch blade pivotally mounted near the bottom of the recess, one set of terminals 20 connected to a common conductor, carried in a passage extending longitudinally through

the base, said base being provided with spaced passages extending transversely for receiving conductors, one of which connects with a switch blade and another with the 25 other switch terminal, said bases being provided at their outlets with a counter bored portion for receiving an insulating conductor, the conductor leading to last named switch terminal being provided with a spark gap disposed on a longitudinally extending groove slidably mounted therein, the conductors leading to the gap being adapted to connect with the spark plugs and the other conductors with the terminals of sparking coils.

In testimony whereof I affix my signature in presence of two witnesses.

OTTO T. PAPKE.
